PRESSING MACHINE

George W. Johnson, Norwood, Ohio, assignor to
 The American Laundry Machinery Company,
 Cincinnati, Ohio, a corporation of Ohio

Application August 31, 1933, Serial No. 687,671

19 Claims. (Cl. 68—9)

This invention relates to pressing machines and particularly to a pressing machine which is automatically and intermittently operated to bring a pressing member alternatively before an operator for arranging the lay of the work and then into registration with a pressing head to complete the pressing operation.

One object of my invention is to provide a pressing machine embodying a plurality of movable padded beds or bucks and a plurality of fixed heated pressing heads together with suitable driving mechanism for automatically and intermittently moving the padded beds selectively into and out of position before the operator or beneath a pressing head.

Another object of my invention is to provide a single pressure applying actuator and means for connecting the actuator alternatively with each of the beds to move it onto pressing engagement with its respective head when the pressing members are in registering position.

Another object of my invention is to provide a motor for moving a pressing bed or beds into and/or out of registration with a coacting pressing head.

Another object of the invention relates to a control apparatus whereby the movement of a bed to position under its respective head automatically causes actuation of the pressure applying unit to raise the bed into pressure engagement with the head, and whereby the release of pressure and the lowering of the bed automatically causes actuation of a power unit to move the bed from its registering position to an open position adjacent the operator.

Still another feature has to do with a novel snubbing mechanism for retarding the moving parts at the ends of their path of travel.

Other objects and advantages of my invention will be apparent from the following description taken with the accompanying drawing in which Fig. 1 is a front elevation of a pressing machine showing the parts in position to move a bed upwardly into engagement with a head; Fig. 2 is a partial front elevation of a pressing machine showing the position of the parts after the bed has been moved upwardly into engagement with the head; Fig. 3 is a section along the line 3—3, of Fig. 1; Fig. 4 is an enlarged detail partly in section of a valve and operating parts for controlling the bed reciprocating motor; while Fig. 5 is an enlarged detail view partly in section of valves and operating mechanism for controlling the flow and exhaust of fluid to the pressure applying cylinder.

My invention comprises a pressing machine embodying spaced pressing beds and pressing heads, the beds being interconnected and adapted to be intermittently moved from a single central position common to both beds and intermediate

the spaced pressing heads into a position of registration with their respective coactive pressing heads, together with means for reciprocating the beds into and out of their respective positions and means for moving the beds into and out of pressing engagement with their respective heads.

The embodiment illustrated comprises a pair of spaced beds mounted on a carriage or support and adapted to travel in a substantially horizontal path, along which are arranged spaced pressing heads. The distance between the centers of the heads is approximately twice the distance between the centers of the companion beds, whereby only one of a pair of beds may be in registry with a head, while the other bed is in exposed position between the spaced heads and accessible to an operator. A single power unit is located intermediate the spaced heads and a member mounted on the bed carriage serves alternatively to supply closing pressure between the power unit and that one of the beds which at the time is in registering position beneath its coacting head. An automatic interlock actuates the power unit in pressure applying direction when one of the beds reaches registering position, and a second power unit acting automatically at the end of the pressing operation moves one of the beds out of registration with its head while at the same time moving the other bed into registration with its companion head.

My invention is embodied in a machine comprising frame members 10, 11 and 12 which support rails 13 and 14 along which a bed support or carriage 15 is adapted to move on rollers 16. The carriage is illustrated as supporting two beds 17 and 18 having downwardly extending stems 19 and 20 permitting vertical movement of the beds with respect to the carriage. Suitable means is provided for maintaining the beds in alignment during their vertical movement, such as the extended flanges 21 and dowel pins 22. Mounted on the frame members 10 and 12 are stationary heads 23 and 24 adapted to coact with beds 17 and 18. These heads may be provided with heating means, as desired, in any manner known to the art. The rail 13 is shown with a V-shaped head and the cooperating rollers 16 are suitably grooved so as to maintain a straight path of travel, while the rollers coacting with rail 14 are plain so as to avoid any possible binding which might occur if both sets of rollers were grooved.

The parts are shown in Fig. 1 with bed 17 in registration with head 23 preparatory to applying pressure to engage the bed with its head. A pressure applying member is mounted on the carriage to alternatively connect a power unit, mounted centrally of the machine, with whichever bed happens to be in registering position. The structure shown for accomplishing this purpose com-

prises a pressure applying lever 25 pivotally mounted on the carriage as at 26 and having its ends bent downwardly and inwardly to form forks 27 and 28 which are adapted to engage a plunger connected with a power unit. This power unit is illustrated as a fluid motor 29 having a cylinder 30, a piston 31 and a piston rod or plunger 32 which is embraced by the aforementioned forks alternatively. Fluid pressure supplied to motor 29 is controlled by inlet valve 34 and outlet valve 35. Valve 34 admits pressure from a suitable source, as conduit 33, to the common inlet and exhaust conduit 36 leading to cylinder 30, while valve 35 connects conduit 36 in turn with exhaust conduit 37 leading to the atmosphere. A spring 38 serves to return piston 31 to its upward or inoperative position when pressure is relieved by the opening of exhaust valve 35.

Means is provided for automatically actuating the control mechanism for the power unit when either head reaches registering position. The mechanism illustrated comprises a cam 39 mounted on the bed carriage and having a notch at each end into which a control lever for the power unit moves. In the position of the parts shown in Figs. 1, 2 and 5, a follower 41 carried by a control lever 42 moves into cam notch 40 under the action of spring 43 when bed 17 comes into registering position beneath head 23. This movement of control lever 42 closes exhaust valve 35 and opens inlet valve 34, thus admitting pressure above piston 31, driving the piston and plunger downwardly, which carries the right hand end of pressure applying arm 25 downwardly, as seen in Fig. 2, and raises the left hand end of the arm into engagement with stem 19 of bed 17, thus causing pressure engagement between the pressing members. At the completion of the pressing operation, the operator actuates a control handle 44 connected with control lever 42, moving said lever in a clockwise direction, which closes valve 34 and opens valve 35 exhausting the pressure from cylinder 30 and permitting the bed to move downwardly out of pressing engagement with the head, due to the weight of the parts.

Means is provided for automatically moving a bed out of registration with its companion head at the close of the pressing operation, and, of course, since the two beds are on a common carriage, such movement of one bed out of registering position moves the other bed into registering position beneath its companion head. The means provided comprises a power unit arranged to give the bed support or carriage a kick sufficient to move it along the rails as far as required. For this purpose, I have shown fluid motors 45 and 46 mounted at opposite ends of the carriage runway, the parts of which are identical and will therefore be described in connection with motor 45 only. Motor 45 has a piston 47 and a suitable plunger 48 adapted to contact the carriage 15 and normally maintained in its retracted position by spring 49. The fluid pressure supply to this reciprocation motor 45 is controlled by a valve 50 adapted to supply fluid pressure from a suitable outside source, as conduit 51, through conduit 52 to motor 45. The motor cylinder is provided with a small outlet port 53 which does not interfere with the building up of operating pressure in the cylinder, but serves to exhaust the cylinder after the completion of a power stroke. Valve 50 is arranged to be actuated automatically upon movement of the pressing members out of pressing engagement and, to this end, an actuating mechanism for the valve is provided

which is cocked by movement of the carriage 15 into the position where one of the beds registers beneath its companion head and this places the said mechanism in position to be operated by the downward movement of the pressure applying lever 25 after the completion of the pressing operation. This control mechanism is the same for valves 50 and 50a and will be described in connection with valve 50 only. A lever 54 is pivotally mounted on the frame as at 55 and is adapted to contact the stem 56 of valve 50. A second lever 57 is pivotally mounted on lever 54 and has an abutment 58 which limits its movement in clockwise direction. A coil spring 59 serves to maintain lever 57 in its position at the limit of its clockwise movement which is somewhat past dead center, as shown in Fig. 2, where it is adapted to act as a pressure applying strut to move lever 54 clockwise. The cocking of the control mechanism for valve 50 is accomplished by arranging lever 57 in position to be contacted by a projection 60 of pressure arm 25 when this arm is moved to the left with carriage 15, as seen in Figs. 1 and 4. This moves lever 57 counter-clockwise without affecting lever 54. Upon the application of pressure between bed 17 and head 23, as shown in Fig. 2, projection 60 moves upward and lever 57 is moved clockwise by action of spring 59 to a position directly beneath projection 60. Thereafter, upon completion of the pressing operation, when the left hand end of pressure applying arm 25 moves downward, projection 60 contacts lever 57, thus moving lever 54 in a clockwise direction and opening valve 50 which admits fluid pressure as before described to reciprocation motor 45 and causes plunger 48 to kick carriage 15 to the right, whereupon bed 17 moves to open position and bed 18 moves into registration beneath its companion head 24.

In this latter position fork 28 of the pressure applying arm 25 embraces plunger 32 of the power unit 29 and follower 41 of control lever 42 enters notch 40a of cam 39 and thereupon the pressing operation occurs between bed 18 and head 24 in a manner similar to that already described.

For snubbing or retarding the moving parts, that is, the bed carriage and its associated parts at the ends of its path of travel, I provide inclined friction pads 61 and 62 at opposite ends of the bed carriage arranged to coast yieldingly with similar pads 63 and 64 mounted on the frame. To this end, pad 63 is mounted on bell crank 65, pivoted to the frame at 66 and arm 67 of the bell crank is yieldingly biased in a clockwise direction by spring 68 carried on a rod 69 connected with the frame. This serves to retard the motion of the carriage and associated parts as they reach the limit of their horizontal travel and the parts are finally brought to rest by a cushioning spring 70 which engages a suitable boss 71 on the carriage. Similar parts at the other end of the machine are similarly numbered with the addition of the suffix *a*.

The operation of the pressing machine is as follows: With the parts in the position shown in Fig. 1, work arranged on bed 17 is ready to be pressed against head 23. When carriage 15 reaches the left-hand limit of its travel, follower 41 moves into cam notch 40. Control lever 42 moves counter-clockwise, closing outlet valve 35 and opening inlet valve 34 to admit fluid pressure above piston 31. Plunger 32 moves downwardly which carries fork 27 of pressure applying lever 25 downwardly. This moves the left-hand end of lever 25 upwardly

and causes pressure engagement between bed 17 and head 23. When the pressing operation is completed and the operator has arranged the lay of the work on bed 18, she depresses control handle 44 which closes inlet valve 34 and opens exhaust valve 35, thus relieving pressure in cylinder 30 and permitting bed 17 to move downwardly out of engagement with head 23. On this downward movement projection 60 of lever 25 engages the control mechanism for valve 50 (in the position shown in Fig. 2), opens valve 50, and admits fluid pressure to motor 45, whereupon plunger 48 kicks bed carriage 15 to the right. When the parts come to rest by the action of snubbers 64 and 70a, follower 41 moves into cam notch 40a to cause pressure engagement between bed 18 and head 24. The operator then removes the pressed work from bed 17, arranges a new lay and depresses control handle 44. Pressure is again relieved in cylinder 30, bed 18 is lowered from head 24, projection 60a of lever 25 operates valve 50a and motor 46 kicks carriage 15 to the left.

It will thus be apparent that I have provided a pressing machine wherein one power unit causes pressure engagement between a plurality of spaced beds and heads by means of a simple arrangement of a pivoted pressure applying lever mounted on the bed carriage.

Pressure can be applied only when the coacting press members are in registering position because the forks on lever 25 are short and engage the plunger of the power unit only when the pressing members are in alignment.

A very efficient means for reciprocating the bed carriage is provided in the motor having a short stroke which gives a powerful kick.

Efficient snubbing means is provided for stopping the carriage.

The entire operation follows automatically upon depression of the control handle by the operator.

What I claim is:

1. A pressing machine comprising two spaced interconnected pressing beds adapted to travel in a path, two spaced pressing heads arranged along said path to alternatively coact with one bed while exposing the other bed, one fluid pressure actuated cylinder and piston motor for causing pressing engagement between the heads and beds, and means carried by said beds for operatively connecting said motor with that bed only which is in position to coact with one of said heads.

2. A pressing machine comprising two spaced interconnected pressing beds adapted to travel in a path, two spaced pressing heads arranged along said path to alternatively coact with one bed while exposing the other bed, one power means for causing pressing engagement between the respective heads and beds, and control means for the power means actuatable in press-closing direction by movement of the bed support into one of its registering positions.

3. A pressing machine comprising two spaced interconnected pressing beds adapted to travel in a path, two spaced pressing heads arranged along said path to alternatively coact with one bed while exposing the other bed, one power means for causing pressing engagement between the respective heads and beds, control means for the power means actuatable in press-closing direction by movement of the bed support into one of its registering positions, and operator-operated means for actuating said control means in press-opening direction.

4. A pressing machine comprising a bed sup-

port arranged to travel in a path, two spaced pressing beds upon said support, two spaced pressing heads arranged along said path to alternatively coact with one of said beds while exposing the other of said beds, a pressure applying actuator intermediate the pressing heads, and a pressure applying lever pivotally mounted on said support and movable to two positions in each of which one end of said lever operatively engages one or the other of said beds while the opposite end of said lever in each position operatively engages said actuator.

5. A pressing machine comprising a bed support arranged to travel in a path, two spaced pressing beds upon said support, two spaced pressing heads arranged along said path to alternatively coact with one of said beds while exposing the other of said beds, mechanism carried by the bed support and adapted to cause pressing engagement between a bed and a registering head, said mechanism having a part extending to a point intermediate said heads, power means positioned at said point, and said part being movable into operative connection with said power means by movement of said support to register a bed and head.

6. A pressing machine comprising a bed support arranged for travel in a path, a reciprocation motor for causing said travel, two spaced beds carried by the support, two spaced pressing heads arranged along said path and adapted to alternatively coact with one bed while exposing the other bed, a pressure applying member carried by the bed support, means for applying pressure to said member to close the press, and means for actuating the reciprocation motor by movement of the pressure applying member in press-opening direction.

7. A pressing machine comprising a bed support arranged for travel in a path, a reciprocation motor for causing said travel, two spaced beds carried by the support, two spaced pressing heads arranged along said path and adapted to alternatively coact with one bed while exposing the other bed, a pressure applying member carried by the bed support, means for applying pressure to said member to close the press, control means for the reciprocation motor, an actuator for said control means, and said actuator being so arranged that it is cocked by movement of the pressure applying lever in press-closing direction and operated by movement of said lever in press opening direction.

8. A pressing machine comprising, coacting pressing members, one member being movable along a straight horizontal path out of registration with the other, fluid pressure actuated means for causing pressing engagement between said members, fluid pressure actuated means for causing said movement out of registration, and means for causing actuation of said last-named means operable automatically upon movement of said members out of pressing engagement.

9. A pressing machine comprising a plurality of pressing beds and a plurality of pressing heads adapted to coact with the respective beds, fluid pressure actuated means for moving one bed out of registration with its companion pressing head while moving another bed into registration with its companion pressing head, a control valve for said bed moving means, means for causing pressing engagement between the respective heads and beds, and means for causing actuation of said bed moving means, including a part having an operative connection with said bed and adapted to actuate said control valve upon movement of a

bed out of pressing engagement with its coacting head.

10. A pressing machine comprising a plurality of pressing beds and a plurality of pressing heads adapted to coact with the respective beds, carriage means for moving one bed out of registration with its companion pressing head while moving another bed into registration with its companion pressing head, fluid pressure actuated means for causing pressing engagement between the respective heads and beds, and cam means on said carriage means for causing operation of said last-named means automatically upon movement of a bed into registration with its companion head.

15. 11. A pressing machine comprising a plurality of pressing beds and a plurality of pressing heads adapted to coact with the respective beds, a carriage for moving one bed out of registration with its companion pressing head while moving another bed into registration with its companion pressing head, a member mounted on the carriage for causing pressing engagement between the respective heads and beds, means for actuating said member automatically upon movement of a bed into registration with its companion head, and means actuated by said member for causing movement of said carriage automatically upon movement of a head and bed out of pressing engagement.

30. 12. A pressing machine comprising two spaced interconnected pressing beds arranged to travel in a path, two spaced pressing heads along said path and arranged to alternatively coact with one of said beds and to expose the other of said beds, and a fluid motor having a piston with a short stroke arranged to kick a bed into and/or out of registration with a head.

35. 13. A pressing machine comprising a frame, a bed supporting carriage arranged to travel therealong and inclined friction pads at opposite ends of the bed carriage arranged to coact yieldingly with similar pads carried by the frame.

40. 14. In a pressing machine of the class described, the combination of a carriage arranged for travel in a horizontal path, a bed supported on said carriage for vertical movement relative thereto, a head positioned above the path of travel of said carriage and bed, motion transmitting means on said carriage for lifting said bed into engagement with said head when said head and bed are in registration, and means for moving said carriage and bed out of registration comprising a cylinder having a piston with operative connections adapted to contact said carriage when 45 fluid is admitted to said cylinder, a control valve which when opened admits fluid to said cylinder, said valve being the sole means for controlling the flow of fluid to said cylinder, and means for opening said valve when said bed moves out of engagement with said head.

50. 15. In a pressing machine of the class described, the combination of a carriage adapted to travel in a path, two pressing beds spaced apart on said carriage, two spaced pressing heads arranged along said path to coact with one of said beds while exposing the other of said beds, means for moving said carriage alternatively to register each bed with its respective head, each of said beds being adapted to be moved relative to said carriage into engagement with a head, motion transmitting mechanism movable with the carriage and adapted to move each of said beds into pressure engagement with their respective heads,

and one power means positioned to have an operative connection with the motion transmitting mechanism of each bed in turn as each bed reaches registering position.

5. 16. In a pressing machine of the class described, the combination of a carriage arranged for travel in a horizontal path, a bed supported on said carriage for vertical movement relative thereto, a stationary head positioned above the path of travel of said carriage and bed, means for moving said carriage to move the bed into and out of registration with the head, power means positioned adjacent the out of registration position of said bed, motion transmitting means on said carriage for lifting said bed, said motion 10 transmitting means including a lever pivotally mounted on the carriage, one end of said lever being adapted to lift the bed from the carriage and the other end of said lever being adapted to engage said power means when the bed registers 15 with the head, and automatic means for actuating said power means to close the press when said bed registers with said head.

17. A pressing machine comprising a carriage adapted to travel in a horizontal path, means for moving said carriage, two spaced pressing beds upon said carriage and vertically movable relative thereto, two spaced pressing heads arranged along said path alternatively to coact with one of said beds while exposing the other of 30 said beds at a point intermediate the heads, a pressure applying actuator adjacent said point, a lever pivotally mounted on said carriage, said lever having one end arranged to lift a bed relative to the carriage, and the other end of said 35 lever and said actuator being arranged to move said lever in bed lifting direction when said bed registers with a head.

18. A pressing machine comprising a carriage adapted to travel in a horizontal path, means for 40 moving said carriage, two spaced pressing beds upon said carriage and vertically movable relative thereto, two spaced pressing heads arranged along said path alternatively to coact with one of said beds while exposing the other of said beds 45 at a point intermediate the heads, a pressure applying actuator adjacent said point, motion transmitting mechanism on said carriage, said mechanism having one portion arranged to lift a bed relative to the carriage, and another portion 50 of said mechanism and said actuator being arranged to move said mechanism in bed lifting direction when one of said beds registers with a head.

55. 19. A pressing machine comprising a bed support arranged to travel in a path, power means located adjacent said path, two spaced pressing beds upon said support, two spaced pressing heads arranged along said path to alternatively coact with one of said beds while exposing the 60 other of said beds, mechanism carried by the bed support and adapted to cause pressing engagement between each bed and its registering head, said mechanism having two parts adapted for engagement alternatively with said power means, each part acting through said mechanism to operate its respective bed, and said parts being arranged for operative connection with said power means by movement of said bed support alternatively to place one or the other of said 65 beds in registry with its coacting head.
